Primary Examiner — Garth Rademaker*Assistant Examiner* — Joseph J. Seddon(74) *Attorney, Agent, or Firm* — Meunier Carlin & Curfman LLC(57) **CLAIM**

The ornamental design for a paper sheet with a pattern as shown and described herein.

DESCRIPTION

FIG. 1 is a top plan view of the paper sheet with a pattern showing our new design according to a first embodiment; and,

FIG. 2 is a top plan view of the paper sheet with a pattern showing our new design according to a second embodiment. The dot-dash broken lines in FIGS. 1-2 around the paper sheet with a pattern show the boundary of the claim and forms no part of thereof.

1 Claim, 2 Drawing Sheets(56)
